United States Patent Office.

JOHN F. BOYNTON, OF SYRACUSE, NEW YORK.

Letters Patent No. 96,876, dated November 16, 1869.

IMPROVED FIRE-EXTINGUISHER.

The Schedule referred to in these Letters Patent and making part of the same.

I, JOHN F. BOYNTON, of Syracuse, in the county of Onondaga, and State of New York, have invented certain Improvements in Fire-Extinguishers, of which the following is a specification.

My invention relates to that class of machines in which a stream of water, or water holding salts in solution, and highly charged with carbonic-acid gas, is injected upon the fire by the pressure of such gas, generated within such machine by the decomposition of suitable chemicals.

In the drawings—

Figure 1 represents a sectional view of my apparatus, and

Figure 2, an elevation of the same.

My apparatus consists of a closed vessel, A, provided with an opening in the top for the admission of water, chemicals, &c., and a tube, d, and stop-cock at the bottom, through which the contents of the vessel may be discharged.

To the outside of the vessel A, near the top, is attached a generating-vessel, b, which communicates with the said vessel A by means of tubes, x x', which may be provided with stop-cocks, if desired.

This generating-chamber consists of a small vessel, of metal or other suitable material, and contains a capsule, of glass or other material, which may be broken or pierced within it, by means of pressure from the screw-rod c. In case a metal capsule is used, I make a small projection on the bottom of the generating-

chamber, to pierce through the metal when pressure is brought to bear upon the capsule by the screw-rod c.

To charge the apparatus, the vessel A is filled with a solution of some suitable carbonate, said solution entering the generating-chamber a through pipes x x'. The capsule b is filled with acid and placed in the generating-chamber a, after which the top is secured, and the apparatus is ready for use. On turning the screw-rod c, its lower end is caused to press against, and break or pierce the capsule b, liberating the acid, which, mixing with the carbonate-solution, decomposes it, and creates the required pressure in the generator and vessel A. The sulphuric acid with which the capsule is generally filled, being much heavier than the carbonate-solution, readily flows from the generator into the vessel A, containing the carbonate-solution, through the connecting-tube x, while the water flows from the vessel A into the generating-chamber through the tube x', thus producing a speedy and thorough mixture of the acid with the carbonated water.

I claim, as my invention—

The combination of the vessel A with the generator a and capsule b, substantially as herein described.

JOHN F. BOYNTON.
